UNITED STATES PATENT OFFICE

93,765

DESIGN FOR A SPECTACLE FRAME

Ernest E. Emons, Kennett Square, Pa., assignor
to The Ful-Vue Sales Company, Washington,
D. C.

Application January 12, 1934, Serial No. 50,382

Term of patent 14 years

To all whom it may concern:

Be it known that I, ERNEST E. EMONS, a citizen of the United States, residing at Kennett Square, in the county of Chester and State of Pennsylvania, have invented a new, original, and ornamental Design for a Spectacle Frame, of which the following is a specification, reference being had to the accompanying drawing, forming a part hereof.

Figure 1 is a perspective view of a spectacle frame showing my new design;

Figure 2 is a front elevation of the same with the temples omitted; and

Figure 3 is a side elevation with the end of the temple being broken away for convenience in illustration.

The dominant feature of this design resides in the contour of the lens, rims, and contour of the supports for the temple connections and in their disposition with respect to the lens rims.

I claim:

The ornamental design for a spectacle frame, substantially as shown and described.

ERNEST E. EMONS.
